FLYING MACHINE

Filed Oct. 6, 1921

2 Sheets-Sheet 2

UNITED STATES PATENT OFFICE.

FRANK L. HEYDON, OF PONCA, NEBRASKA.

FLYING MACHINE.

Application filed October 6, 1921. Serial No. 505,959.

To all whom it may concern:

Be it known that I, FRANK L. HEYDON, a citizen of the United States, residing at Ponca, in the county of Dixon, State of Nebraska, have invented a new and useful Flying Machine; and I do hereby declare the following to be a full, clear, and exact description of the invention, such as will enable others skilled in the art to which it appertains to make and use the same.

The invention relates to flying machines of the manually operated type, and has for its object to provide a device of this character which is provided with oppositely rotated propellers, said propellers being rotated by means of a pedal operated gear, which gear has a gear and shaft connection with the propellers.

A further object is to provide a flying machine comprising a wheel supported frame, a pair of spaced propellers supported forwardly of the frame, said propellers having shaft connections with spaced oppositely disposed bevelled gears and gear and shaft connections with a pedal operated gear whereby the bevel gears of the propeller shafts are simultaneously rotated in opposite directions, thereby allowing the manually operated flying machine to glide and rise into the air.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:—

Figure 1 is a side elevation of the machine.

Figure 2 is a front elevation.

Figure 3 is a vertical sectional view through the gear casing, showing the drive gears for the propeller shafts.

Figure 4 is an enlarged detail view of a portion of the pedal operated drive gear and the shaft carried gear connected therewith.

Referring to the drawings, the numeral 1 designates spaced gliding planes, which planes are carried by a frame 2. The frame 2 is provided with a rearwardly extending portion 3, to which is secured in any suitable manner an elevating plane 4 and a lateral guiding plane 5. Extending down-

wardly from the frame 2 are brackets 6, in which are mounted an axle 7, and on which axle wheels 8 are rotatably mounted. The wheels 8 roll over the ground during a taking off or landing operation. Disposed within the frame 2 is a frame 9, which frame is provided with a seat 10 for the operator and a gear casing 11 in which is rotatably mounted a bevel gear 12, said level gear being adapted to be rotated by means of pedals 13 on which the operator places his feet while seated on the seat 10. Extending upwardly from the gear casing 11 and having a bearing in one side thereof and a bearing in a gear casing 14 is a shaft 15, the lower end of which shaft is provided with a bevel gear 16 meshing with the drive gear 12, and its upper end with a bevel gear 17, which is geared to the horizontally disposed bevel gear 18 by means of an idle gear 19. It will be seen that when the gear 12 is rotated by the operator that the gear 18 will also be rotated, thereby imparting rotation to the horizontally disposed gear 20 carried by the shaft 21, which shaft is mounted in anti-frictional bearings 22 in a wall 23 of the casing 14. The anti-frictional bearings take up the thrust of the shaft 21 and its gears, and also reduces the friction to a minimum. Disposed within the gear casing 14 are spaced bevelled gears 24 and 25, with which gears the bevel gear 20 meshes, in such a manner that no matter in which direction the bevel gear 20 is rotated the bevel gears 24 and 25 will be rotated in opposite directions. The bevel gear 25 is carried by a propeller drive shaft 26, the forward end of which is provided with a propeller 27. The bevel gear 24 is provided with a sleeve 28 through which the shaft 26 extends and in which the shaft 26 rotates, said sleeve being provided with a propeller 29. It will be seen that when the gears 24 and 25 are rotated in opposite directions the propellers 27 and 29 will be simultaneously rotated in opposite directions, thereby causing the flying machine as a whole to be propelled forwardly.

The planes 4 and 5 may be controlled in any suitable manner by the operator. Extending downwardly and forwardly from the upper plane 1 are braces 30, which braces assist in bracing and supporting the casing 14.

From the above it will be seen that a manually operated flying machine is provided

which is simple in construction, and one so constructed that the operator may rotate the propellers while seated on a seat above a drive gear, which drive gear is provided with pedals. It will also be seen that the propellers 27 and 29 are driven through gear mechanism which are simple in construction and in such a manner that said propellers will rotate in opposite directions at the same speed, thereby increasing the pulling power; and at the same time preventing side movement of the device as a whole incident to the right hand or the left hand propeller. Extending downwardly, and inwardly from the gear casing 14 are braces 31, which braces are attached to the forward edge of the lower plane 1, said braces 31 in connection with the braces 30 forming the supporting means for the gear casing 14.

20 The invention having been set forth what is claimed as new and useful is:—

25 A flying machine comprising a frame, an operator's seat disposed on said frame; a main drive gear disposed below said operator's seat, pedals carried by said drive gear whereby the operator may rotate the same with his feet, a pair of propellers mounted on shafts and disposed adjacent the forward 30 end of the frame, one of said propeller

shafts being rotatably mounted in the other propeller shaft and having its inner end extending beyond the inner end of the other shaft, bevelled gears in opposed positions carried by said shafts and spaced from each other; said bevelled gears and shafts being carried by a frame supported casing, a bevelled gear disposed between said shaft carried bevelled gears and meshing therewith, a downwardly extending shaft carried by the last named bevelled gear, a bevelled gear carried by the lower end of the last named shaft, an angularly disposed downwardly and rearwardly extending drive shaft, a bevelled gear carried by the upper end of said last named shaft, an idle gear connecting the last named bevelled gear and the bevelled gear carried by the lower end of the downwardly extending shaft and a bevelled gear carried by the lower end of the downwardly and rearwardly extending shaft and meshing with the drive gear.

40 In testimony whereof I have signed my name to this specification in the presence of two subscribing witnesses.

FRANK L. HEYDON.
